W. J. CAHILL

SPARK PLUG

Filed March 12, 1920

FIG. 1.

FIG. 3.

William J. Cahill
INVENTOR.

By
Dewitt E. Hodges
ATTORNEY.

UNITED STATES PATENT OFFICE.

WILLIAM J. CAHILL, OF SAYRE, PENNSYLVANIA.

SPARK PLUG.

Application filed March 12, 1920. Serial No. 365,239.

To all whom it may concern:

Be it known that I, WILLIAM J. CAHILL, a citizen of the United States of America, residing at 403 North Elmer Avenue, Sayre,

5 in the county of Bradford and State of Pennsylvania, have invented certain new and useful Improvements in Spark Plugs, of which the following is a specification.

This invention relates to improvements in 10 spark plugs for internal combustion engines and has for an object to provide an improved structure which will be air proof, having all connections completely housed in a simple and efficient manner.

15 Another object of the improvement is to have the insulating member carrying one of the terminals readily removable and adjustable relative to the other terminal without the necessity of removing the casing 20 of the plug from the engine.

Another object of the improvement is to have the terminal which connects the feed wire to one of the terminals arranged axially with the terminal and outer protective 25 casing whereby the latter may be readily removed without the necessity of disconnecting the wire and terminal.

Figure 1, is a longitudinal section through the spark plug.

30 Figure 2, is a horizontal transverse section on line 2—2 of Figure 1.

Figure 3, is a detail view of the central terminal and connections.

1, indicates a casing having external 35 threads 2, at the lower end adapted to be screwed into the cylinder and support the contact terminal 3, properly within the cylinder. The casing is further provided with internal screw threads as at 4, at the outer 40 end thereof and a central bore 5, restricted at the lower end to form a shoulder or seat 6. An insulating member 7, is fitted into the central bore of the casing being held in place by means of the protecting 45 casing 8, screwed into the internal screw threaded portion of the casing 1.

The insulating member 7, preferably consists of a plurality of convolutions 9, preferably mica, surrounded by a collar 10, 50 provided at its upper end with a annular flange 11, beveled on its under side to coincide with the shoulder 6, in the casing whereby a tight joint is effected, the annular flange being of sufficient thickness to engage 55 the wall of the casing to properly center the insulating member and the central terminal

12, carried thereby with respect to the lower contact terminal 3, in order that a proper air gap between the two contact terminals may be assured.

60 The protecting casing 8, is provided with a threaded aperture 13, at the upper end thereof to receive a knurled bushing 14, through which the feed wire 15, is passed. The contact terminal 12, is threaded at 65 its upper end and is adapted to receive a threaded sleeve 16, into the upper end of which is detachably secured by a set screw 17, the exposed end of the wire 15. This arrangement permits the 70 wire and terminal being securely fastened together after which the protecting casing 8, is passed down over the connection screwed into the casing to hold the insulating member firmly in place and form a 75 water tight covering for the connections. The bushing 14, is then secured into place thereby closing the aperture in the protecting casing.

80 The protecting case can, of course, be made of an insulating material but preferably consists of a metal body lined with an insulating material 18. With such a construction the casing may be readily removed without disturbing the connections between the center terminal and the feed wire, and if desirable the central terminal and insulating member may be readily removed 85 for cleaning without removing the entire plug from the cylinder.

90 I claim,

A spark plug comprising an internally flanged casing, an insulating shell provided with a flanged collar adapted to seat in said flanged casing, a terminal carried by said 95 insulating shell, a protective casing having threaded engagement with the upper end of said internally flanged casing adapted to surround and hold said insulated shell in position, said protective casing being provided with an aperture in the upper end thereof, an orificed bushing removably received in said aperture, and a feed wire passing therethrough and connected with the terminal carried in the insulating shell, said 100 feed wire and terminal being in axial alignment, whereby the protective casing may be removed longitudinally for exposing said terminal connection and the removal of said insulating shell.

110 In testimony whereof I affix my signature.

WILLIAM J. CAHILL.
